UNITED STATES PATENT OFFICE.

JOHN REYNOLDS, OF BLAKELY, OLYPHANT, PENNSYLVANIA.

DESIGN FOR A DRINKING-GLASS.

49,936.

Specification for Design.

Patented Nov. 21, 1916.

Application filed October 4, 1916. Serial No. 123,779. Term of patent 3½ years.

To all whom it may concern:

Be it known that I, JOHN REYNOLDS, a citizen of the United States, residing at Blakely, Olyphant, in the county of Lackawanna and State of Pennsylvania, have invented a new, original, and ornamental Design for Drinking-Glasses, of which the following is a specification, reference being had to the accompanying drawing, forming part thereof.

The figure is a perspective of a drinking glass showing my new design.

I claim:

The ornamental design for drinking glass, as shown.

JOHN REYNOLDS.

Witnesses:

JOHN W. JAMES,
MICHAEL SNYDER.
